[57] CLAIM

The ornamental design for a combined luggage wheel
mounting plate and wheel assembly, as shown and de-
scribed.

DESCRIPTION

FIG. 1 is a perspective view of a combined luggage
wheel mounting plate and wheel assembly showing my
new design, the structure shown in broken line being for
illustration purposes only;

FIG. 2 is an enlarged scale bottom plan view thereof;
FIG. 3 is a side elevational view of an alternate form
thereof wherein the wheel assembly is mounted in a
reverse position on the mounting plate; and

FIG. 4 is a side elevational view thereof.

FIG. 1

FIG. 2

FIG. 3

FIG. 4
